(57)

CLAIM

The ornamental design for a barbecue fork as shown and described.

DESCRIPTION

1. Barbecue fork

1.1 : Perspective

1.2 : Perspective

1.3 : Perspective

1.4 : Front

1.5 : Back

(Continued)

1.6 : Left

1.7 : Right

1.8 : Top

1.9 : Bottom

The broken lines in the reproductions depict portions of the barbecue fork that form no part of the claimed design.
